UNITED STATES PATENT OFFICE

117,267

DESIGN FOR A CHAIR

Aaron S. Goldberg, Philadelphia, Pa.

Application February 28, 1939, Serial No. 83,256

Term of patent 7 years

To all whom it may concern:

Be it known that I, Aaron S. Goldberg, a citizen of the United States and a resident of Philadelphia, county of Philadelphia, State of Pennsylvania, have invented a new, original, and ornamental Design for a Chair, of which the following is a specification, reference being had to the accompanying drawing forming a part thereof, wherein:

The figure is a perspective view of a chair showing my design.

I claim:

The ornamental design for a chair, as shown.

AARON S. GOLDBERG.
